UNITED STATES PATENT OFFICE.

FRANCIS W. CASEY, OF ROCKLAND, MASSACHUSETTS.

FIREWOOD-CUTTING MACHINE.

Application filed July 7, 1922. Serial No. 573,422.

To all whom it may concern:

Be it known that I, FRANCIS W. CASEY, a citizen of the United States, residing at Rockland, in the county of Plymouth and 5 State of Massachusetts, have invented new and useful Improvements in Firewood-Cutting Machines, of which the following is a specification.

This invention is embodied in a machine 10 adapted to cut into short lengths for fuel, the tops and branches of trees known as "slash", the object being to enable slashings to be rapidly and economically reduced to form suitable for use in stoves and furnaces, 15 thus utilizing material which is usually wasted, because of the absence of suitable means for advantageously adapting it for such use.

The invention may also be embodied in a 20 machine adapted to cut into lengths, sticks, such as trunks and branches of larger diameter than so-called slashings.

Of the accompanying drawings forming a 25 part of this specification,—

Figure 1 is a side elevation of a machine embodying the invention.

Figure 2 is a fragmentary end elevation on a smaller scale, showing an attachment hereinafter described.

Figure 3 is a top plan view, omitting the 30 guide extension shown by Figure 1.

Figure 4 is a side elevation, and

Figure 5 is an end elevation showing a 35 casing enclosing the mechanism of the machine.

Figure 6 is an end elevation, the casing being removed.

Figure 7 is a section on line 7—7 of Figure 3.

Figure 8 is a section on line 8—8 of Figure 3.

Figure 9 is a section on line 9—9 of Figure 3.

Figure 10 is a perspective view of the 45 fixed shear blade removed from the machine.

Figure 11 is a perspective view of the head plate, which carries the fixed blade.

Figure 12 shows a length as cut from a 50 slashing by the machine.

The same reference characters indicate the same parts in all of the figures.

The frame of the machine includes bearings 12, for a power-driven shaft 13, bearings 14 for a driving-shaft 15, and suitable 55 base members 16 supporting said bearings.

The driven shaft 13 is connected with the driving shaft by gears 17 and 18, and the driving shaft may be connected with any suitable source of power, as by a belt running on a pulley 19, fixed to the driving 60 shaft.

Fixed to the driven shaft 13 is a revolving shear blade 20, having a cutting edge 21, which is in a plane at right angles to the shaft. The portion of the blade on which the cutting edge is formed is cam-shaped, the cutting edge having a salient curvature and being eccentric to the shaft. I prefer to secure the blade 20 by screws 22, to an arm 23, having a hub 23^a, which is connected by a key 65 24 with the shaft 13. The arm is countersunk or recessed to form a shoulder bearing on the edge or end face of the blade. The blade is beveled on one side, and the cutting edge intersects the opposite or outer side, 70 which is essentially flat and in a plane at right angles to the shaft.

Secured to a head plate or bracket arm 25, forming a part of the frame of the machine, is a fixed shear blade 26, having a cutting 80 edge 27, which is preferably a portion of the wall of an aperture 27^a in a flat-sided plate forming the body of the fixed blade. The head plate 25 has a recess 25^a in one side, formed to receive the fixed blade 26, the latter being detachably secured to the head plate by screws 28. The fixed blade 26 has a flat side facing the flat outer side of the revolving blade 20, and in a plane at right angles with the shaft. Said sides are so arranged that the revolving knife is in sliding contact with the blade 26, during a part of each revolution, so that its cutting edge 21 is adapted to cooperate with the fixed cutting edge 27 in severing material with a shearing 85 cut. The wall of the aperture 27^a intersects the side of the fixed blade at an angle which constitutes in effect, the fixed cutting edge.

As shown by Figures 7 and 10, the fixed cutting edge, which is the portion of the 100 wall at the left, and lower portions of the wall of the aperture 27^a, as shown by Figure 10, has a reentrant curvature, and is eccentric to the shaft 13. The form and arrangement of the fixed cutting edge is such that 105 the cutting edge of the revolving blade alternately passes across, and recedes from the fixed cutting edge, as indicated by dotted lines in Figure 7. When the revolving blade recedes, a throat is formed between the cut- 110

ting edges of the two blades for the reception of material feed to the machine. When the revolving blade approaches and passes across the fixed blade, the cutting edges cooperate in severing the inserted material with a shearing cut.

As shown by Figure 11, the head plate 25 has an aperture 25^b corresponding in form to the aperture 27^a in the fixed blade. When 10 the revolving blade 20 is in the left-hand position shown by Figure 7, the apertures 25^b and 27^a are practically unobstructed, and form a receiving throat of maximum area. Material inserted in the throat while it is 15 thus unobstructed is forced toward the fixed cutting edge 27 by the revolving blade. The head plate 25 is provided with a guide 30, formed as an endless flange surrounding the aperture 25^b and projecting from the outer 20 side of the head plate. Said guide is inclined or obliquely arranged, so that it directs the material obliquely between the cutting edges, as indicated by the arrow X in Figure 1, and by the arrow Y in Figure 3. 25 The material is, therefore, so presented to the cutting edges that the line of cut is oblique, as shown by Figure 12, which shows a section 33 cut from a slashing, 34, 34 being the oblique ends formed by the cutting action.

The guide may be provided with an extension 32, as shown by Figure 1. To regulate or determine the length of the sections 33, I provide a stop 35, spaced from the 35 inner sides of the blades, and in the path of material inserted in the guide, so that the advancing ends are arrested at a predetermined distance from the line of the cut. The stop 35 is preferably a disk fixed to 40 the shaft 13. Its forward side against which the material abuts is preferably knurled or roughened, as indicated by Figure 6, to engage the ends of the slashings or other pieces. The stop may be adjustable toward and from the blades to vary the 45 length of the cut sections.

To prevent the blades from being gummed with pitch in cutting wood such as pine, the attachment shown by Figures 1 and 50 2 may be provided, this being embodied in an elevated tank 37, adapted to contain a solvent, such as kerosene oil, and provided with a feed pipe 38, discharging against the flat side of the revolving blade, and 55 controlled by a cock 39.

The head plate 25 is preferably adjustable, to permit lateral adjustments of the fixed blade. To this end the head plate is provided with a base 40, secured to portions of the frame by screws 41, in slots 42 60 in the base. Adjusting screws 43 are provided, bearing on one edge of the base 40. When the screws 41 are loosened, and the screws 43 are turned in one direction, the 65 head plate is moved toward the path of

the revolving blade, and may then be secured by tightening the screws 41. When the screws 43 are turned in the opposite direction, they recede and permit movement of the head plate away from the path of 70 the revolving blade. These lateral adjustments are of course very slight, and are intended chiefly to compensate for wear of the blades.

A sheet metal cover 44 (Figures 4 and 5), 75 may be provided, to protect the described mechanism.

The head plate 25, and the fixed blade 26 may be provided with coinciding orifices 45 (Figures 10 and 11), arranged to receive 80 a portion of the shaft 13.

I do not limit myself to a machine adapted only to cut slashings into lengths. A machine embodying the described construction may be adapted to cut tree trunks 85 and limbs with or without branches and twigs into lengths suitable for firewood. I have successfully used the machine driven by a three H. P. engine to cut trunks or sticks about three inches in diameter. By 90 suitably increasing the power and the strength of the blades, trunks or sticks of considerably greater diameter may be cut. The guide which conducts the material to the blades may be flaring, and decrease in 95 diameter from its outer to its inner end, so that a trunk of suitable diameter, and its branches and twigs, may be fed as a unit into the machine. The material may be fed either by hand or mechanically.

I claim:

1. A firewood-cutting machine comprising a frame, a power-driven shaft journaled in fixed bearings on the frame, a revolving shear blade fixed to the shaft and having a cutting edge in a plane at right angles to the shaft, the blade being cam-shaped, so that its cutting edge has a salient curvature, and is eccentric to the shaft, and a fixed shear blade having a cutting edge 105 with a reentrant curvature, and in a plane parallel with the edge of the revolving blade, said edges being in shearing relation to each other, the arrangement being such that the revolving blade alternately recedes from the fixed blade to form a receiving throat, and approaches the fixed blade to close said throat and cooperate with the fixed blade in severing inserted material.

2. A firewood-cutting machine substantially as specified by claim 1, comprising also a guide at the outer sides of the blades, adapted to direct material into said throat in a direction oblique to the plane of the 110 blades.

3. A firewood-cutting machine substantially as specified by claim 1, comprising also a stop at the inner sides of the blades, adapted to arrest the inserted material and 115

determine the length of the sections into which the material is cut by the shear blades.

4. A firewood-cutting machine substantially as specified by claim 1, the said frame including a head plate to which the said fixed blade is secured.

5. A firewood-cutting machine substantially as specified by claim 1, the said frame including a head plate to which the said fixed blade is secured, said head plate and

fixed blade being adjustable toward and from the revolving blade.

6. A firewood-cutting machine substantially as specified by claim 1, the said frame including a head plate to which the said fixed blade is secured, the said head plate and fixed blade being provided with coinciding apertures.

In testimony whereof I have affixed my signature.

FRANCIS W. CASEY.
